UNITED STATES PATENT OFFICE.

WILLIAM ROSENFIELD, OF MANISTEE, MICHIGAN.

HEEL-PLATE AND ICE-CREEPER.

SPECIFICATION forming part of Letters Patent No. 472,396, dated April 5, 1892.

Application filed December 29, 1891. Serial No. 416,436. (No model.)

To all whom it may concern:

Be it known that I, WILLIAM ROSENFIELD, a citizen of the United States of America, residing at Manistee, in the county of Manistee, 5 and State of Michigan, have invented certain new and useful Improvements in a Combined Heel-Plate and Ice-Creeper; and I do declare the following to be a full, clear, and exact description of the invention, such as will enable others skilled in the art to which it appertains to make and use the same, reference being had to the accompanying drawings, and to the letters and figures of reference marked thereon, which form a part of this specification.

15 My invention relates to a combined heel-plate and ice-creeper for boots and shoes; and the object of my improvement is to provide a combined plate and creeper for the purposes stated, which will serve with equal utility to 20 preserve the boot or shoe and which may be readily converted into an ice-creeper whenever the condition of the surface warrants.

In the accompanying drawings, Figure 1 is a view showing the device attached to the heel 25 of a shoe, the creeper being turned with its flat side or surface outward. Fig. 2 is a similar view wherein the creeper is in position with the calks or teeth outward. Fig. 3 is a 30 sectional view on the line $\alpha\alpha$ of Fig. 2. Fig. 4 is a perspective of the device, showing the upper side thereof; and Fig. 5 is a detail of the base-plate.

A designates the base-plate, preferably of the shape shown in the drawings, and consisting of an integral plate having side pieces 1 35 2, connected by a rear piece or bar 3 and a front piece or bar 4. In the connecting bar or piece 3 are formed openings 5, constituting sockets to receive the calks or teeth of the creeper when that element is turned with its flat or smooth surface outward, as seen in Fig. 2 of the drawings. These sockets are 40 preferably made long enough to take in the calks and are formed tapering and sharp, as seen in Fig. 3 of the drawings, so that they 45 may be readily forced into the material to which the device is to be attached. The front bar 4 constitutes a spring and has projecting from it a spring-tongue 6, which engages with the creeper, as shown, and serves to hold that 50 element in position when turned in either direction. The plate is provided with spikes

or nails constituting attaching-prongs 7, by which it is secured to the shoe.

On the side portions of the base-plate A are 55 secured metal taps or lifts 8 9, these being thick enough to reach above the surface of the body of the creeper, so that when the creeper is arranged in its bearings and turned back its face will be free from or above the 60 wearing-surface of the taps. In the edges of the plates are formed bearings 10 11, wherein are pivoted and supported the journals of the creeper, as shown.

B designates the creeper, formed with el- 65 liptical or flattened journals to set in the bearings between the plates, so that the spring function of the plates will aid in holding the creeper flat in either direction to which turned. The creeper is formed with calks or teeth 12 70 to engage a surface, and the calks take in the sockets and are there concealed when the creeper is not in use as such. The creeper also has a finger-piece 13, by which it is ma- 75 nipulated. The spring finger or tongue en- 75 gages the creeper and also serves to throw it flat and hold it in that position.

The uses of my invention are readily perceived from the description; but they may be here rehearsed. The device being secured to 80 the shoe or boot, it is ready for use, and all that is required to do is to turn the creeper in the direction the condition of the surface on which it is to be used indicates.

Having thus described my invention, what 85 I claim, and desire to secure by Letters Patent, is—

1. The combined heel-plate and ice-creeper herein described, consisting of a base-plate having a rear connecting-bar formed with 90 openings to receive the calks of the creeper and a front piece or bar formed with a spring-tongue and having attaching-prongs 7, and an ice-creeper journaled in the plate and formed with calks to engage a surface and adapted 95 to turn back and rest with the calks in the openings of the rear connecting-bar of the base-plate and to be held by the spring-tongue thereof.

2. The combined heel-plate and ice-creeper 100 herein described, consisting of a base-plate A, having side taps 8 9 secured thereto, a rear connecting-piece formed with tapering sockets and a front connecting-bar having a spring-

tongue and having attaching-prongs 7, and an
ice-creeper journaled between the base-plate
and the side taps to ride on the end of the
spring-tongue and formed with calks and
adapted to be turned on its bearings to hori-
5 zontal position front or back, substantially as
and for the purpose specified.

In testimony whereof I affix my signature in
presence of two witnesses.

WILLIAM ROSENFIELD.
